Primary Examiner—Wallace R. Burke*Assistant Examiner*—Marcus Jackson*Attorney, Agent, or Firm*—Frank J. Dykas; Craig M. Korfanta[57] **CLAIM**

The ornamental design for a double panel information sign, as shown and described.

DESCRIPTION

FIG. 1 is a front elevational view of a double panel information sign showing my new design, with the broken lines showing for illustrative purposes only, and forming no part of the claimed design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front elevational view thereof, with the sign portion shown in an alternate position;

FIG. 8 is a rear elevational view thereof;

FIG. 9 is a right side elevational view thereof;

FIG. 10 is a left side elevational view thereof;

FIG. 11 is a top plan view thereof; and,

FIG. 12 is a bottom plan view thereof.
